UNITED STATES PATENT OFFICE

CARL D. BROWN, OF HOPEDALE, MASSACHUSETTS, ASSIGNOR TO DRAPER CORPORATION, OF HOPEDALE, MASSACHUSETTS, A CORPORATION OF MAINE

LET-BACK FOR LOOM TAKE-UPS

Application filed July 19, 1930. Serial No. 469,090.

This invention relates to the take-up mechanism of a loom and has for its object to provide mechanism acting when the take-up driving mechanism is disconnected to effect the required let-back independently of the pull on the warps.

In the weaving of goods of a fine and delicate nature when a let-back of the take-up mechanism is required, the force exerted by the tension of the warps is frequently not sufficient to effect the reverse rotation of the take-up mechanism and consequently a defect is produced in the weaving because of the failure of the take-up mechanism to compensate for the loss of picks or other error in the weaving.

Furthermore, when a let-back action of the take-up mechanism is required in goods requiring extreme accuracy and the take-up roll is driven by a train of gears, the backlash in the gears frequently causes a variation in the amount of let-back and consequently a defect in the fabric woven.

This invention has for its object to provide means for reversing the action of the take-up mechanism and driving it in the reverse direction to the extent required to effect the desired let-back whenever the action of the take-up mechanism is arrested by disengagement of the take-up driving mechanism.

The invention has for its further object to provide a simple and efficient form of mechanism for thus securing the desired let-back in which during the normal taking up action power is stored up in a let-back actuator and then released when the driving mechanism of the take-up is disengaged so that this stored up power acts to reverse the operation of the take-up mechanism and thus effect required let-back.

These and other objects and features of the invention will appear more fully from the accompanying description and drawings and will be particularly pointed out in the claims.

The drawings illustrate a portion of a loom frame and so much of an ordinary type of positively driven take-up mechanism as is sufficient to disclose in connection therewith

a simple and preferred form of the invention.

In the drawings:

Fig. 1 is a side elevation of a portion of the front of the loom.

Fig. 2 is a front elevation of the construction shown in Fig. 1.

Fig. 3 is a detail in vertical cross section taken on the line 3—3 of Fig. 4 showing a construction of the preferred form of let-back actuator employed in this invention.

Fig. 4 is a view in vertical cross section taken on the line 4—4 of Fig. 3.

Only a small portion of a loom is shown involving one side frame 1 with the girt 2 extending across to the other side frame with the shaft 3 carrying the usual take-up roll 4 and extending across the loom and journaled in the two side frames. The take-up mechanism is positively driven in a well-known manner.

As illustrated, a suitable driven shaft 5 mounted in the bracket 6 supported on the loom frame 1 extends fore and aft and carries a worm 7 intermeshing with a worm wheel 8 on a shaft 9 extending transversely at the front of the loom frame. This shaft 9 is connected by a train of gearing with the shaft 3 of the take-up roll. In the construction illustrated, this train of gearing comprises

a pinion 10 journaled on the shaft 9, a gear 11 and connected pinion 12 journaled in the bracket 13 with the gear 11 intermeshing with the pinion 10, a gear 14 and connected pinion 15 journaled on the stud 16 mounted in the loom frame with the gear 14 intermeshing with the pinion 12, a gear 17 journaled on the stud 18 mounted in the loom frame and intermeshing with the pinion 15, and a gear 19 secured to the shaft 3 of the take-up roll and intermeshing with the gear 17.

An ordinary type of clutch comprising a fixed member 20 secured to the pinion 10 and a spring-pressed movable member 21 keyed to the shaft 9 enables the pinion to be connected to and to be disengaged from the driven shaft 9. The end of a lever 22 is shown for moving the clutch member 21 in opposition to its spring 23 away from the clutch member 20 to effect disengagement when the taking up action of the take-up

mechanism is to be arrested as, for example, through the action of a filling fork when the filling breaks during the weaving operation.

All of the mechanism thus described is well known and familiar to those skilled in the art. During the normal weaving operation the clutch parts 20 and 21 are in engagement and the take-up roll 4 is being positively driven to effect take-up from the driving member or shaft 9 through the driven member or pinion 10 and the intermediate train of gearing extending to the take-up shaft 3. When take-up action is to be arrested and let-back take place, the clutch member 21 is automatically moved to the left in opposition to its spring 23 by the lever 22 and thus the driving member is disconnected from the driven member of the mechanism.

In the present invention a let-back actuator is provided, a preferred construction of which is shown in detail in Figs. 3 and 4. This device is in engagement with the train of gearing interposed between the driven member of the take-up roll and is preferably located at the end of the train of gearing remote from the take-up roll. It is conveniently mounted upon the bracket 13, which bracket, as is usual, is supported on the shaft 9 and adjustably secured to the loom frame so as to provide for changing the size of gears employed in the gear train.

This let-back actuator, in the specific form illustrated, comprises a journal stud 24 mounted in and projecting from the bracket 13; a cup-shaped spring case 25 having a hub 26 journalled on the stud 24; a coiled spring 27, similar to a clock spring, concentrically mounted in the spring case and secured at its inner end, as by the pin 28, to the bracket 13 and frictionally engaging at its outer end the interior of the spring case; an annular cover 29 secured by the screws 30 to the end of the spring case and enclosing the spring; a pawl 31 journalled on a stud 32 screwed into the spring case near its periphery and parallel with the stud 24 and normally pressed inward by a spring 33; a pinion 34 journalled coaxially with the spring case and for that purpose conveniently journalled on the hub 26 of the spring case; and a ratchet 35 on the pinion 34 and cooperating with the pawl 31. A washer 36 and pin 37 on the outer end of the stud 24 hold the parts in position. The pinion 34 intermeshes with the gear 11.

It will thus be seen that as the train of gearing is driven to effect the take-up action of the take-up mechanism, the pinion 34 will be driven by the gear 11 and act through the pawl 31 to drive the spring case, thus winding up the spring until the frictional engagement between the outer end of the spring and the spring case is overcome and slippage takes place. When now the driving member or element such as the shaft 9 is disconnected from the driven member or element such as

the pinion 10 of the take-up mechanism to arrest take-up, the power stored up in the spring 24 during the take-up action is released and immediately the direction of rotation of the pinion 34 is reversed and the pinion is driven by the spring and in turn drives the train of gearing and consequently the take-up roll also in the reverse direction, effecting let-back to the extent provided by the power stored up in the spring. Thus the take-up roll is positively driven in the reverse direction, quite independently of the pull on the warps, to effect a definite and required amount of let-back.

Any suitable connection may be employed between the spring case 25 and the pinion 34, but the pawl and ratchet mechanism illustrated permits relative rotary adjustment of the spring case with respect to the pinion and transmits the spring-actuated movement of the spring case to the pinion in all positions.

There is thus provided a simple and efficient mechanism by means of which, when the driving member of the take-up mechanism is disengaged from the driven member, the driven member is driven in a reverse direction to a limited extent thus positively to effect let-back.

Having thus described the invention, what is claimed as new, and desired to be secured by Letters Patent, is:

1. Take-up mechanism for a loom comprising a take-up roll, a driving member, a train of gearing between said driving member and take-up roll, means to disengage the driving member from said gearing to arrest take-up, a pinion intermeshing the gearing, a spring case, the said pinion and spring case being concentrically journalled on the loom frame, a coiled spring concentrically mounted in said case and secured at one end to the frame and at the other end frictionally engaging the case, and a connection between the case and pinion, the said pinion acting during take-up to rotate the case and store up power in the spring and the said spring acting upon disengagement of the driving member to rotate the pinion in reverse direction to effect let-back.

2. Take-up mechanism for a loom comprising the construction defined in claim 1 in which the connection between the case and pinion is in two parts co-operating to permit relative rotary adjustment of the case and pinion.

3. Take-up mechanism for a loom comprising the construction defined in claim 1 in which the connection between the case and pinion comprises a ratchet wheel on the pinion and a spring-pressed pawl on the case co-operating with the ratchet wheel to permit relative rotary adjustment and to transmit the spring-actuated movement of the case to the pinion.

4. A let-back actuator for take-up mechanism for a loom comprising a journal stud mounted in the loom frame, a spring case journalled on the stud, a coiled spring mounted concentrically in the spring case secured at one end to the frame and at the other end frictionally engaging the case, a pawl pivotally mounted on the case, a pinion journalled co-axially with the spring case and 10 a ratchet on the pinion co-operating with the pawl.

5. A let-back actuator for take-up mechanism for a loom comprising a journal stud mounted in the loom frame, a spring case 15 having a hub journalled on the stud, a coiled spring mounted concentrically in the spring case secured at one end to the frame and at the other end frictionally engaging the case, a pawl pivotally mounted on the case, 23 a pinion journalled on the hub of the case, and a ratchet on the pinion co-operating with the pawl.

In testimony whereof, I have signed my name to this specification.

CARL D. BROWN.
